his Attorney

UNITED STATES PATENT OFFICE.

WALTER D. NICKUM, OF GLENDALE, CALIFORNIA, ASSIGNOR TO JOHN C. LEWIS, OF PORTLAND, OREGON.

ELECTRIC GASIFIER FOR INTERNAL-COMBUSTION ENGINES.

1,247,992.

Specification of Letters Patent. Patented Nov. 27, 1917.

Application filed February 20, 1917. Serial No. 149,848.

To all whom it may concern:

Be it known that I, WALTER D. NICKUM, a citizen of the United States, residing at Glendale, in the county of Los Angeles and 5 State of California, have invented a new and useful Electric Gasifier for Internal-Combustion Engines, of which the following is a specification.

This invention relates to means for heating 10 the charge, or mixture of air and fuel, passing to the intake of an internal combustion engine, so as to gasify the fuel, and the main object of the present invention is to provide means for effecting such heating independently of or in conjunction with heat 15 furnished from the exhaust, so as to enable convenient and rapid starting of the machine.

Another object of the invention, especially 20 in the case of an automobile engine, is to provide for such preheating of the charge passing to the engine by means which can be conveniently controlled by the chauffeur without leaving his seat.

25 The accompanying drawings illustrate embodiments of the invention and referring thereto:

Figure 1. is a vertical section, partly in elevation, of one form of the invention.

30 Fig. 2. is a section on line 2—2 in Fig. 1, the electric connections being indicated diagrammatically in the figure.

Fig. 3. is a side elevation showing the connections of the device to the engine supply 35 and exhaust means.

In Figs. 1 and 2 the invention is shown as applied in connection with heating means utilizing the heat of the exhaust to heat the incoming charge; said heating means comprises for example, a casing 1 provided with a chamber 2, having inlet and outlet passages 3 and 3', whereby it may be connected to pipes indicated at 4 and 4' for conducting the exhaust gases therethrough and said casing 1 being formed with a vertical passage 5 extending within the chamber 2 and connected for example, by pipe connections indicated at 6 and 7 to receive the charge or mixture of air and fuel passing from the carbureter 9 to the intake means of the engine. Said chamber 2 is also shown as provided with a branch 8, or passage means, which extends through the passage 5 aforesaid, so that part of the exhaust gases pass directly through this additional passage 45 means 8, sufficient space being left at each side of the walls of this passage means to permit flow of the incoming charge upwardly around said passage means. A perforated sheet 5', for example of wire gauze, 60 is preferably placed across the passage 5. The above described construction is not claimed herein, but is illustrated as showing a form of a mixture heater, with which my invention is specially adapted for use. 65

My invention comprises an electric heating element or unit mounted on the central passage means 8 aforesaid, so as to be exposed to the incoming mixture or charge as it passes upwardly around said passage 70 means 8. Said heating unit may consist of a cup shaped casing 11 screwing into the bottom wall of said passage means 8; a heating coil 12 of resistance wire mounted in said casing and insulated therefrom by means of 75 insulation indicated at 14, a cap member 10 screwing on the said casing 11, and means for supplying current to said resistance coil or wire. In order to supply current to the resistance coil or wire, any suitable connection means may be used, for example a metal rod or wire 15 may extend through a tube 16 mounted on the outer casing 1 and through an insulating plug 17 mounted within the heating unit casing 11 and into 80 a contact pin 18 mounted within said insulating plug, the said wire or rod 15 being insulated as indicated at 20 and being provided with suitable means, such as nuts 21 at its outer end for connecting a circuit wire 90 thereto. The device described may in the case of an automobile engine be energized and operated by current from the usual battery of the ignition plant or of the lighting plant; the battery, indicated at 23, being 95 connected by wire 24 to a switch 25, from which a wire 27 leads to the terminal means 21 aforesaid. One end of the resistance wire is connected by screw 29 to the connecting wire 15 and the other end is connected by 100 screw 30 to the resistance unit casing 11, which is grounded or connected through the metal parts of the apparatus with the other side of the battery, ground connections to the latter being indicated by dotted line 32. 105 The controlling switch 25 may be conveniently located on the dash board or elsewhere convenient to the chauffeur.

The operation of the device above described is as follows: In starting the ma- 110

chine, the switch 25 is closed and the current from battery 23 flows through wire 24, switch 25, conducting rod 15, pin 18, resistance wire 12, casing 11, and through 5 "ground" back to the battery. The heat generated by the current flowing through the resistance wire warms the casing 11 of the heating unit and also warms the adjacent part of the wall or passage 8, so that 10 the mixture of air and atomized fuel passing from the carbureter to the engine intake is heated by contact with the parts so warmed, sufficiently to vaporize or gasify any liquid fuel present in the mixture and insure explosion or combustion of the mixture when 15 it is compressed and ignited in the cylinder, and also insure that all of the fuel will be carried forward with the mixture and that none will be condensed on the walls of the 20 passages. By preheating the charge in this manner starting of the engine is insured and accelerated, even under unfavorable conditions, for example, when the fuel is difficult to gasify, either by reason of the engine being cold, or by reason of the lack of volatility of the fuel. In fact with this device 25 it is possible to use distillate or similar cheap and comparatively non-volatile fuels, without involving any difficulty in starting 30 the engine, or requiring priming or starting with gasolene, or preheating with torches, etc. Moreover, the device may be brought into operation by the chauffeur, without leaving his seat, and when the engine is well 35 under way the electric heating device may be cut out of operation, by opening switch 25, while the vehicle is in motion, so as to utilize the heat of the exhaust; passing through the passage means 8 and chamber 40 2, for heating the mixture, and thereby reduce the demands on the battery. In general, the electrical pre-heating means need be operated for only a minute or so so that dry batteries may be used therefor if desired.

The above described construction has the advantage that by mounting the electric heating element in a wall portion that surrounds an exhaust passage and extends

through the mixture passage, the same metal that is utilized to conduct heat from the exhaust gases to the mixture is also used to conduct heat from the electric heating element to the mixture. Moreover, as the electric heating element is completely surrounded by the mixture, the heat from said element is fully utilized in heating the mixture.

What I claim is:

1. In combination with an internal combustion engine and a carbureter connected to the intake thereof, a heating means connected to receive exhaust gases from the engine, and provided with a passage connected to receive mixture passing from the carbureter to the engine, and having a wall adapted to receive heat from said exhaust gases and to transmit such heat to the mixture in said passage, and an electric heating element mounted in said wall of said passage in such manner as to transmit heat from said electric heating element to said mixture through the same wall that transmits the heat to the mixture from the exhaust gases.

2. In combination with an internal combustion engine having a carbureter, an intake connection from said carbureter to the engine and an exhaust connection from the engine, a heating means comprising passage means connected in the connection from the carbureter to the engine and a passage connected to receive exhaust from said exhaust connection and extending through said passage means so as to be surrounded by mixture from the carbureter, and an electric heating element mounted in a wall portion of said passage and adapted to electrically heat the mixture passing therethrough by transmission of heat from the electric heating element through said wall portion, said wall portion also being adapted to transmit heat from the exhaust gases to the mixture passing to the engine.

In testimony whereof I have hereunto set my hand, at Los Angeles, California, this 10th day of February 1917.

WALTER D. NICKUM.
